COMBINED SEWING MACHINE BED EXTENSION AND ATTACHMENT BOX

Walter D. Szuba, Westfield, and Edward A. Bruder,
Roselle, N.J., assignors to The Singer Manufacturing
Company, Elizabeth, N.J., a corporation of New Jersey

Filed June 15, 1961, Ser. No. 65,611

Term of patent 14 years

(Cl. D70—2)

Fig.1

Fig.2

Fig. 3

Fig. 4

Fig. 5

Fig. 8

Fig. 7

Fig. 6

FIG. 1 is a front perspective view of a combined sewing machine bed extension and attachment box, showing our new design,

FIG. 2 is a view similar to FIG. 1 but with the cover of the attachment box open,

FIG. 3 is a reduced scale top plan view,

FIG. 4 is a reduced scale front elevational view,

FIG. 5 is a reduced scale right side elevational view,

FIG. 6 is a reduced scale left side elevational view,

FIG. 7 is a reduced scale rear elevational view, and

FIG. 8 is a reduced scale bottom plan view.

We claim:

The ornamental design for a combined sewing machine bed extension and attachment box, substantially as shown.
